My design consists of a square game board having a cruciform pattern of circular depressions thereon with a cluster of five circular depressions within a square between each arm of the cruciform in combination with a rectangular channel, having a molded grid-like pattern at its base, extending around the entire periphery of the board. Said channel is divided into four compartments by walls extending at 45° angles from the corners of the board to the corners of the playing area, all as shown.

I claim:

The ornamental design for a game play board, as shown and described.
